William Stanley Jr.,

UNITED STATES PATENT OFFICE.

WILLIAM STANLEY, JR., OF PITTSBURG, PENNSYLVANIA.

SYSTEM OF ELECTRICAL REGULATION.

SPECIFICATION forming part of Letters Patent No. 372,942, dated November 8, 1887.

Application filed August 22, 1885. Serial No. 175,045. (No model.)

To all whom it may concern:

Be it known that I, WILLIAM STANLEY, Jr., a citizen of the United States, residing in the city of Pittsburgh, in the county of Allegheny 5 and State of Pennsylvania, have invented certain new and useful Improvements in Systems of Electric Lighting, of which the following is a full and exact specification.

In other applications filed of even date here- 10 ic with I have described a method of regulation to be applied to a system of electrical distribution, in which incandescent electric lamps are located in groups of branch circuits in series to each other, the lamps in each group 15 being in parallel arc to each other. In such a system all the current from the generator of electricity passes through each group of lamps and a part of it inversely proportional to the number of lamps through each lamp in a 20 group.

In case of the throwing out of circuit of one or more lamps in a group, the remaining lamps are liable to be broken by reason of the increased amount of current passing through 25 them. This I have provided for in the devices described in the applications above referred to by substituting an equivalent resistance for each lamp thrown out of circuit. Lamps are also liable to be broken in case of an increase 30 in the quantity of current flowing through the line. To obviate this danger is the object of my present improvement, and I accomplish this object by substituting for each lamp that is thrown out of circuit such a resistance that, 35 in case of an increased flow of current, the increase will pass through the resistance rather than through the illuminating lamps in circuit, and so leave the latter intact.

It is well known that the resistance of a carbon filament decreases as its temperature increases, and I make application of this principle in carrying out my invention. For each illuminating incandescent lamp in circuit I provide in a separate circuit a resistance-lamp 45 and suitable mechanism for automatically putting in circuit the corresponding resistance-lamp when an illuminating-lamp is thrown out of circuit or broken. The current which before passed through the illuminating-lamp will 50 then pass through the carbon of the resistance-lamp, which is so proportioned that it will

be heated about to redness, or to such a point that its resistance will readily vary with changes of temperature, and will then have a resistance equivalent to that of the lamp for 55 which it is substituted. If then, when one or more of the resistance-lamps are in circuit, there should be an increase in the current flowing in the main, the temperature of the carbon in the resistance-lamp will at once be increased and its resistance correspondingly lowered, so that an increased proportion of the current will pass through it. This in turn produces a further increase of temperature and decrease of resistance until all the current 60 above the normal amount passes through the resistance-lamp to the relief of the illuminating-lamps still in circuit. Should there be a dangerous increase of current in the main while all the illuminating-lamps in a group are 65 in circuit, the weakest carbon will be first broken, the corresponding resistance-lamp substituted for it, and the remaining illuminating-lamps relieved by the shunting action of the resistance-lamp. 70

I have illustrated suitable devices for carrying my invention into effect in the drawings, in which L L' represent two parts of a divided main conductor, between which are branch circuits x x' x'' x''', in which are included incandescent lamps l l' l'' l'''. In each of the circuits x is an electro-magnet, M, having a pivoted armature of conducting material, which, when not sustained by the attraction of the magnet, closes and forms part of a circuit 80 in which is included a resistance-lamp, R. So long as the illuminating-lamps are in circuit the armatures are upheld by the magnets; but when any lamp-circuit is broken the armature of the magnet falls and closes the circuit 85 through the corresponding resistance-lamp. 90

While the illuminating-lamps in a group may be somewhat widely separated—as all the lamps in a building, for example, may be included in one group—the corresponding resistance-lamps may, if desired, be located together at a convenient place, and when in a state of incandescence will by their appearance indicate what members of the group of illuminating-lamps are out of circuit. The 95 conductors leading from the respective resistance-lamps R R' R'' R''' are united in a con- 100

ductor, *y*, leading to the conductor *L*. In this conductor *y* there is included an electro-magnet, *E*, provided with an armature, *A*. This armature is normally held back by a spring, 5 *e*, and will be drawn to its electro-magnet only when the latter is traversed by a current resulting from currents through all the resistance-lamps *R* *R'* *R''* *R'''*. A contact-point, *B*, upon the lever *A* is provided with front contact-springs, *c*, and these are respectively connected with the conductors *L* and *L'*, so that when the several resistance-lamps *R* have all been brought into circuit the electro-magnet *E* will be vitalized and a short circuit completed through the conductors *z z*, thus cutting out the entire station. The lever *A* will stay in its forward position by reason of the pressure of the springs *c*.

Having thus described my invention, what 20 I claim as new, and desire to secure by Letters Patent, is—

1. The combination, substantially as herein-before set forth, of two supply-conductors, incandescent electric lamps included in multiple 25 arc between the same, an artificial resistance-circuit for each of said lamps normally open

with reference thereto, devices included in the respective circuits of the lights for completing the respective circuits upon the cessation of the normal current through the lamps, and 30 an electro-magnetic cut-out included in circuit with all of said artificial resistance-circuits and serving when operated to complete a short circuit between the conductors, substantially as described. 35

2. The combination, substantially as herein-before set forth, of two supply-conductors, electric lights included in multiple arc between the same, a conductor leading from one of the supply-conductors, an electro-magnet included 40 in said conductor, branch conductors leading from said conductor, artificial resistances included in the respective branch conductors, means for connecting the respective branch conductors with the remaining supply-conductors, and a short circuit between said supply-conductors closed by the action of said electro-magnet. 45
